UNITED STATES PATENT OFFICE.

HARRY B. FOX, OF PERU, INDIANA.

GARMENT.

1,247,254.

Specification of Letters Patent. Patented Nov. 20, 1917.

Application filed October 2, 1915. Serial No. 53,736.

To all whom it may concern:

Be it known that I, HARRY B. FOX, a citizen of the United States of America, residing at Peru, in the county of Miami and 5 State of Indiana, have invented certain new and useful Improvements in Garments, of which the following is a specification, reference being had therein to the accompanying drawing.

- 10 This invention relates to garments and has for its object the production of a simple and efficient garment which is reinforced at the points thereof which are adapted to receive the greatest amount of wear.
- 15 Another object of this invention is the production of a simple and efficient reinforcing means which is firmly and efficiently secured to the garment at certain points to prevent the garment from being torn when 20 severe pressure is brought to bear thereon or when suddenly pulled upon or jerked.

With these and other objects in view, this invention consists of certain novel combinations, constructions, and arrangements of 25 parts as will be hereinafter fully described and claimed.

In the accompanying drawings:—

Figure 1 is a front elevation of a combination garment, showing the reinforcing 30 means formed thereon.

Fig. 2 is an elevation of the inner face of one of the legs of the garment.

Fig. 3 is an elevation of the arm-hole of 35 the garment, showing the reinforcing means thereon.

Fig. 4 is a section taken on line 4—4 of Fig. 2.

Fig. 5 is a section taken on line 5—5 of Fig. 2.

40 Fig. 6 is a section taken on line 6—6 of Fig. 2.

Fig. 7 is a section taken on line 7—7 of Fig. 3.

Fig. 8 is a rear elevation of a portion of 45 the combination garment, showing the lacing guides formed around the waist-line of the garment.

Fig. 9 is a section taken on line 9—9 of Fig. 8.

50 Referring to the accompanying drawings by numerals it will be seen that 1 designates the body of the garment which may be provided with the usual arm holes 2, if so desired when the body of the garment is cut to 55 form what is commonly known as a com-

bination garment. A reinforcing strip 3 is firmly secured to the inner face of the garment and constitutes a substantially segmental reinforcing strip having its upper or outer edges conforming to the contour of 60 the arm-hole 4 as illustrated, in Fig. 3 of the drawings. This reinforcing strip 3 extends for a considerable distance below the arm-hole 4 and upon either side of the side seam 5 of the garment so as to protect the arm-hole along the bottom thereof against unusual strain or wear.

By carefully considering Figs. 1 and 2, the reinforcing means of the leg sections will be clearly understood. The lower portions of the garment comprising the leg sections is provided with a backwardly folded seam 6 extending around the entire inner edge of the leg section for constituting an opening between the leg sections. The opening 7 formed between the leg sections is so formed as to extend for practically the entire length of the leg section, allowing only a short bridge portion 8 between the bottom of the leg and the opening or slit 7.

By carefully considering Fig. 4, it will be seen that the inner edge of the leg section has the edges folded backwardly for constituting a seam 9 and the reinforcing strip 10 is fitted in the inner face of each leg 85 section and has a backwardly bent portion 11 fitted under the backwardly bent portion or seam 9 of the leg section. These backwardly bent portions 9 and 11 are stitched in a firm position by means of the stitches 12. 90 A binding tape 13 passes over the seams 9 and 11 and has the edges thereof firmly secured to the leg sections by means of the strip 14. This structure is clearly illustrated in Fig. 4 of the drawings. The reinforcing strips 10 have their side edges cut to conform to the contour of the leg section and the inner side edges are firmly stitched below the hem or seam 6 as illustrated clearly 95 in Fig. 2 of the drawings. These reinforcing strips 10 are firmly stitched along their outer faces 15 to the leg sections of the garment and thereby constitute an efficient reinforcing means for the leg section of the garment at the very point where the greatest amount of strain takes place, especially when the slit portion of the garment, comprising the leg sections thereof are drawn quickly apart.

It should be understood that the reinforce- 110

ing strips 10 may constitute a means for reinforcing the leg portions of the garment and will at the same time prevent the garment from being torn at the point where 5 the greatest amount of strain takes place when the opening between the leg sections are quickly drawn apart or to an open position.

In Figs. 8 and 9 there is shown a portion 10 of the garment known as the waist-line, wherein a draw string guide is inserted having a plurality of spaced apertures 17 formed therein, through which a draw string 18 passes for the purpose of permitting 15 the union or combination garment to be drawn together around the waist of the wearer.

From the foregoing description it will be seen that a very simple and efficient device 20 has been produced for permitting a garment to be manufactured out of thin material and at the same time cause the garment to be thoroughly reinforced at the points of the greatest amount of wear, and at the same 25 time prevent the garment from being accidentally torn or ripped when sudden strain is brought to bear upon the garment.

Copies of this patent may be obtained for five cents each, by addressing the "Commissioner of Patents, Washington, D. C."

What I claim is:—

As a new article of manufacture, a garment comprising a pair of leg sections, each section provided with a binding tape extending around the inner edge thereof, said garment provided with an opening between said leg sections, the opening extending substantially throughout the entire length of one side of each leg section, each leg section provided with a joining seam for connecting the edges of the leg sections, each section also provided with a reinforcing strip tapering toward the seam of the leg section, the reinforcing strip being placed upon opposite sides of the seam, said reinforcing strips extending entirely across the leg sections from the inner edge of the opening between the leg sections to the bottom ends of the leg sections, a reinforcing binding tape extending over the adjoining edges of the reinforcing strips for thoroughly bracing and reinforcing the leg sections at the point of greatest strain when the leg sections are 50 pulled apart.

In testimony whereof I hereunto affix my signature.

HARRY B. FOX.
